(57) CLAIM

The ornamental design for detachable scissors as shown and described.

DESCRIPTION

FIG. 1 is a perspective view of detachable scissors showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the detachable scissors;

FIG. 10 is another exploded perspective view thereof; and, FIG. 11 is a perspective view of the detachable scissors where the detachable scissors is in a configuration of use. The broken lines in the drawings depict portions of the detachable scissors that form no part of the claimed design.
